CERTAIN QUATERNARY AMMONIUM COMPOUNDS

Melvin De Groote, University City, and Bershard Keiser, Webster Groves, Mo., assignors to Petrolite Corporation, Wilmington, Del., a corporation of Delaware

Application April 4, 1955, Serial No. 499,196

13 Claims. (Cl. 260—295)

The present invention has a number of aspects. One aspect is concerned with the conversion of a certain specific type of polyalkyleneglycol, as hereinafter described, into a carboxyl derivative in which the carboxyl group contains a labile chlorine atom followed by reaction with the tertiary amine.

A second aspect is concerned with the product so derived by the above procedure.

A third aspect is concerned with uses for such polyalkyleneglycol derivatives and particularly uses other than the resolution of petroleum emulsions.

Attention is directed to our co-pending application, Serial No. 499,197, filed April 4, 1955, in which we have

which water, propyleneglycol, or low molal propyleneglycol is oxypropylated by means of any suitable catalyst, either acid or alkaline, and then subjected to oxyethylation. Instead of being a single step process, one may employ a two-step process in which oxypropylation takes place first and then oxyethylation. If desired, one can simply purchase a suitable polypropyleneglycol from any one of a number of sources and subject the product to oxyethylation as hereinafter specified. If desired, one can purchase the oxyethylated propyleneglycols in the open market and thus the first step is merely esterification, followed by the second step which involves conversion into a quaternary ammonium compound.

As has been stated previously, the polyalkyleneglycols employed are reactants obtained by the oxyethylation of polypropyleneglycol. In a general way, the composition of such polyalkyleneglycol is such that the molecular weight range varies from approximately 800 up to approximately 10,000. The amount of ethylene oxide present in the compound as compared with the oxypropyleneglycol varies from 10% to 20% up to approximately 80% to 90%. Indeed, this is the generally accepted procedure for the characterization of such product. Thus the table employed by one manufacturer is as follows in which the X marks indicate products regularly available and those available in carload or large quantities appear with specific designations other than an X mark.

TABLE I.—CHARACTERIZATION OF OXYETHYLATED POLYPROPYLENEGLYCOLS

First digit	Ethylene oxide in molecule, percent									
	Second digit									
	0-10 (0)	10-20 (1)	20-30 (2)	30-40 (3)	40-50 (4)	50-60 (5)	60-70 (6)	70-80 (7)	80-90 (8)	90-99 (9)
Molecular weight of base unit:										
Less than 600	(1)									
601-800	(2)									
801-1,000	(3)	X		X			X			X
1,001-1,200	(4)		X		L44				X

1,501-1,800	(6)		L61	L62						
1,801-2,100	(7)			X	L74	X		L77		
2,101-2,500	(8)	X			L84			L87	L88	
More than 2,500	(9)									

pointed out that a narrow sub-genus selected from the broad group herein described is particularly effective for the resolution of petroleum emulsions of the water-in-oil type.

For purpose of convenience, what is said hereinafter will be divided into five parts:

Part 1 is concerned with the preparation of polyalkyleneglycols employed as initial reactants;

Part 2 is concerned with the description of suitable halogenated monocarboxy acids which can be employed in the present invention;

Part 3 is concerned with the preparation of esters by reaction between the two classes of reactants previously noted;

Part 4 is concerned with a description of the tertiary amines which can be employed to convert the esters described in Part 3, preceding, into quaternary or diquaternary compounds;

Part 5 is concerned with uses for the quaternary compounds obtained in the manner described in Part 4 and particularly for applications other than those involving the resolution of petroleum emulsions of the water-in-oil type.

PART 1

The preparation of the polyalkyleneglycols which are used as initial reactants, can be a continuous process in

The manufacture of ethyleneglycol, polyethyleneglycol, propyleneglycol, polypropyleneglycol, and oxyethylated polypropyleneglycol, is well known. One procedure, of course, is to simply oxypropylate water so as to obtain the polypropyleneglycol of the desired molecular weight, for instance, in the range of 500 or thereabouts, to approximately 2500 or 2000, and then to oxyethylate so as to obtain an oxyethylated polypropyleneglycol coming within the indicated range.

However, one need not start with water and one may start with a low molal water-soluble glycol, for instance, propylene, dipropylene or tripropyleneglycol.

If desired one may purchase the polypropyleneglycol in the open market. For instance, one manufacturer regularly manufactures polypropyleneglycol within the following three molecular weight classes, to wit, 400-450;

975-1075; and 1950 to 2100. Higher molecular weights are also available as, for example, at least one product having a molecular weight of approximately 2750 or thereabouts. There are also being offered currently polypropyleneglycols having molecular weights of approximately 3000 and 4000. Thus, if desired one can purchase a suitable polypropyleneglycol and not resort to oxypropylation at all. All that is required is to oxyethylate the polypropyleneglycol obtained in the open market or prepared to specification.

It is not believed that any description of the manufacture of such products is required but purely for purpose of illustration reference is made to U. S. Patent No. 2,674,619, dated April 6, 1954, to Lundsted. In said patent there is a characterization of such products in the following language:

"18. Compounds having improved detergent properties, according to the formula

where y equals at least 15; and $(\text{C}_2\text{H}_4)_x-x'$ equals 20-90% of the total weight of the compound."

In any oxyalkylation procedure of the kind herein described, particularly since a multiple oxyalkylation is involved (i. e., oxyalkylation with at least 2 different oxides), it is well known that one does not obtain a single compound but a cogeneric mixture. Indeed this is true of even the simplest oxyalkylation as, for example, the oxyalkylation of a monohydric alcohol. Reference is made to U. S. Patent No. 2,679,513, dated May 25, 1954, to De Groot with particular reference to columns 19 and 20.

For reasons which have been stated previously, two or three different manufacturers may furnish a polypropyleneglycol 1200 or 1500, or 2000, or even 3000 or 4000, or the like, and although substantially the same there is a slight variation in composition. The reason is due to at least two factors. As pointed out previously one does not get a single product but one obtains cogeneric mixtures whose average composition corresponds to the molecular weight indicated. For instance, one manufacturer of a polypropyleneglycol whose average molecular weight is 1025 states the molecular weight in fact varies from 975 to 1075 and, similarly in the case of a product whose average molecular weight is 2025 the variation runs from 1950 to 2100. Depending on the catalyst used, the rate of reaction and other factors the variation may be even somewhat wider, for instance, 1025 to 1125 in one case and 1900 and 2150 in another case. The other factor is one that has been pointed out a number of times and particularly in a series of articles dealing with derivatives of propylene oxide. See "Les Derives de l'Oxyde de Propylene," parts I, II and III, Industrie Chimique, volume 40, 1953, pages 221-9, 249-58, and 281-6.

Since propyleneglycol has both a primary alcohol and a secondary alcohol radical and since one can look upon polypropyleneglycols as polymeric linear condensation derivatives of propyleneglycol it is obvious one could obtain head-to-head polymerization, tail-to-tail polymerization, and head-to-tail polymerization. This simply means the equivalent of etherization involving 2 primary hydroxyl groups or 2 secondary hydroxyl groups, or a primary and secondary hydroxyl group. This is illustrated by the fact that there are three dipropyleneglycols. If one goes to tripropyleneglycol there are theoretically at least eight possibilities. In the higher polypropyleneglycols these possibilities increase enormously. Thus, the first variation is in the molecular weight size which determines the average molecular weight and the second variation is concerned with the fact that dependent on the method of oxypropylation employed, and various factors such as catalyst used, temperature, pressure, speed of reaction, etc., there may be variations in the actual structure. For this reason solubility in water must be interpreted in light of such fact and, thus, although polypropyleneglycol of an average molecular weight of 1,000 or thereabouts may show solubility of about 1.5% in water actually this may be the solubility of some of the low molal cogener. Thus, it is customary to consider polypropyleneglycols having a molecular weight of 1,000 or more as being substantially water-soluble. Such cus-

tomary use is herein included. Even if the molecular weight is double, up to 2000 or thereabouts, there may even be a trace of the glycol which is water soluble, for instance, somewhere in the neighborhood of .015%.

In subsequent Table II the polypropyleneglycols obtained varied in molecular weight from approximately 1100 to 3600. They were obtained as the equivalent of reacting one mole of water with 18 moles, 20 moles, 24 moles, 28 moles, 32 moles, 38 moles, 42 moles, 46 moles, and 59 moles of propyleneoxide. They were then reacted with small amounts of ethylene oxide; in some cases one to four moles, in other cases two to five moles, or three to six moles, five to seven moles, and in other instances as many as 15 moles of ethylene oxide. Table II gives the data in complete form covering these oxyethylated polypropyleneglycols which were obtained by conventional procedures using an alkaline catalyst. The molecular weight, including the initial mole of water, is shown and also the percentage of the two oxides ignoring the initial moles of water so as to conform to the accompanying drawing.

25

65

PART 2

Having obtained an oxyethylated propyleneglycol of the kind described in Table I as available in the open market or prepared in the manner described in Table II, or variants thereof, the next step is reaction with a suitable halogenated acid as previously noted. The preferred halogen carboxy acid compound is chloroacetic acid. The acylchloride, to wit, chloroacetyl chloride may be used but is more expensive. Other halogen acids, halogen

75

substituted acyl halides, and esterifying derivatives are suitable, particularly alpha-halogen carboxylic acids of not over 6 carbon atoms. When the halogen is in the alpha-position to the CO group, the reaction seems to go with greater readiness. And with the shorter chain esterifying halogen carboxylic acids or their functional equivalents, especially chloroacetyl chloride, the reaction goes with such ease that this may in fact be considered an invention within the broader aspect. Other halogen acylating compounds which are suitable are, for example, alpha-chloropropionic acid, alpha-bromstearic acid, alpha-bromoleic acid, or the acyl halides or anhydrides corresponding to these acids.

PART 3

Esters are obtained by the usual esterification procedures involving the diols as described in Part 1 with the chlorocarboxy acids described in Part 2, preceding. The procedure is illustrated by the following examples.

Example 1b

One mole of oxyethylated polypropyleneglycol L-64 (Table I) or 300 grams was mixed with 1000 grams of xylene in a resin pot with mechanical stirrer and Dean and Stark trap. One mole of chloroacetic acid or 94.5 grams was added and the mixture was heated to 180-195° C. to remove by distillation one mole of water or 18 grams. Xylene distilling over with the water was separated and returned to the resin pot after removal of the water. A nonviscous amber colored water emulsifiable liquid resulted.

Example 2b

The same procedure was followed as in Example 1b, except that instead of one mole of chloroacetic acid, 2 moles or 189 grams were added and the mixture was heated as before to remove 2 moles of water or 36 grams by distillation. A non-viscous amber colored water emulsifiable liquid resulted.

Further examples are illustrated in Tables III and IV, following:

TABLE IV

	Ex. No.	Molar ratio	Temp., °C.	Time, hours	Grams water distilled	Moles water distilled	Grams xylene used
5	1b	1-2	170	3	36	2	500
	2b	1-2	170	3	36	2	500
	3b	1-2	176	8	36	2	1,000
	4b	1-2	180-200	15	36	2	1,000
10	5b	1-2	170	4½	36	2	1,000
	6b	1-2	190	3	36	2	1,000
	7b	1-2	176	8	36	2	1,000
	8b	1-2	173-190	7½	36	2	1,000
	9b	1-2	185-190	7½	36	2	1,000
	10b	1-2	185-190	7½	36	2	1,000
	11b	1-2	170	3	36	2	668
	12b	1-2	180	3	36	2	940
	13b	1-1	180-190	3	18	1	1,000
15	14b	1-2	180	3	36	2	650
	15b	1-2	160-170	8	36	2	1,000
	16b	1-2	180	5	36	2	1,000
	17b	1-2	175-200	3	36	2	1,000

PART 4

Having obtained an ester in which there is one or two halogenated carboxy radicals obtained by reacting a diol of the kind described in Part 1 with either one or two moles of a halogenated acid or its equivalent as described in Part 2, such esters are then reacted with appropriate tertiary amines to give a quaternary ammonium compound. Suitable tertiary amines include pyridine, trimethylamine, triethylamine, tributylamine, triamylamine, etc. These are the typical tertiary amines which are commonly employed in this type of reaction. The production of suitable quaternary compounds in some instances having one quaternary radical and in other instances two, are illustrated subsequently.

The homologues of pyridine, for instance, the low molal alkyl derivatives such as the low molal derivatives of the monoethyl derivatives or the dimethyl or diethyl derivatives, are more expensive than pyridine but ultimately may be available at a cost which makes their use feasible. Such derivatives, as long as there is no interference with the quaternization of the tertiary nitrogen, are suitable.

Example 1c

One molecular equivalent of Example 14b of Table III or 4153 grams, was heated under reflux at 160° C. for one hour with 2 moles of pyridine or 160 grams. Upon cooling a homogeneous water soluble material resulted.

Example 2c

The same procedure was followed as in Example 1c

TABLE III

Ex. No.	Diol*	Moles used	Weight in grams	Acid	Moles used	Weight in grams

PART 5

As has been pointed out previously, one of the subgenera herein described is particularly effective in the resolution of petroleum emulsions of the water-in-oil type as described in our co-pending application, Serial No. 499,197, filed April 4, 1955. The products herein described are effective for a variety of uses where cationic surfactants are employed. It is well known that cationic surfactants have utility in the following fields: Acid detergents; agricultural sprays; anti-static; asphalt; cement; floatation; leather; metals; paints; printing inks; rubber; and textiles.

Reference is made to certain other uses. For instance, the material is valuable as a fuel oil additive in the manner described in U. S. Patent No. 2,553,183, dated May 15, 1951, to Caron et al. It can be used in substantially the same proportions or lower proportions and this is particularly true when used in conjunction with a glyoxalidine, or amido glyoxalidine.

An analogous use in which these products are equally satisfactory, is that described in U. S. Patent No. 2,665,978, dated January 12, 1954, to Stayner et al. The amount employed is in the same proportion or lesser amounts than referred to in said aforementioned Caron et al. patent.

The second use is for the purpose of inhibiting fogs in hydrocarbon products as described in U. S. Patents Nos. 2,550,981 and 2,550,982, both dated May 1, 1951, and both to Eberz. Here, again, it can be used in the same proportions as herein indicated or even smaller proportions.

These materials also have particular utility in increasing the yield of an oil well by various procedures which in essence involve the use of fracturing of the strata by means of liquid pressure. A mixture of these products with oil or oil in combination with a gel former alone, or a gel former and finely divided mineral particles, yields a product which, when it reaches crevices in the strata which are yielding water, forms a gelatinous mass of curdy precipitate or solid or semi-solid emulsion of a high viscosity. In any event, it represents a rapid gelling agent for the strata crevices and permits pressure to be applied to fracture the strata without loss of fluid through crevices, openings or the like.

The herein described products and the derivatives thereof are particularly valuable in flooding processes for recovery of oil from subterranean oil-bearing strata when employed in the manner described in U. S. Patent No. 2,233,381, dated February 25, 1941, to De Groote and Keiser.

Having thus described our invention, what we claim as new and desire to secure by Letters Patent, is:

1. A quaternary ammonium compound of the structure

20 is the residue of the oxyethylated polypropyleneglycol

where $(\text{C}_3\text{H}_6\text{O})_y$ equals at least 10, and $(\text{C}_2\text{H}_4\text{O})_{x+y}$ equals 10-90% of the total weight of the compound, the molecular weight being within the range of approximately 25 800 to approximately 10,000 and

is the radical of the halogenated monocarboxy acid

35 having not over 18 carbon atoms in which R' is composed of carbon and hydrogen atoms, in which n is a small whole number not over 2 and the halogen atom is substituted in the alpha carbon position, and $\text{N} \equiv \text{R}_1$ is the radical of the free tertiary amine $\text{N} \equiv \text{R}_1$ in which R_1 is composed of carbon and hydrogen atoms and represents not over 3 organic radicals having a total of not over 15 carbon atoms which organic radicals collectively satisfy the trivalent nitrogen valency, and R'' is a member of the class consisting of hydrogen and

in which the characters have their previous significance.

2. The quaternary ammonium compound of claim 1 in which R'' is

3. A quaternary ammonium compound of the structure

55 in which ORO is the residue of the oxyethylated polypropyleneglycol

where $(\text{C}_3\text{H}_6\text{O})_y$ equals at least 10, and $(\text{C}_2\text{H}_4\text{O})_{x+y}$ equals 10-90% of the total weight of the compound, the molecular weight being within the range of approximately 800 to approximately 10,000, and

is the radical of the halogenated monocarboxy acid

having not over 18 carbon atoms in which R' is composed of carbon and hydrogen atoms, and the halogen atom is substituted in the alpha carbon position, and $\text{N} \equiv \text{R}_1$ is the radical of the free tertiary amine $\text{N} \equiv \text{R}_1$ in

which R_1 is composed of carbon and hydrogen atoms and represents not over 3 organic radicals having a total of not over 15 carbon atoms which organic radicals collectively satisfy the trivalent nitrogen valency.

4. A quaternary ammonium compound of the structure

in which ORO is the residue of the oxyethylated polypropylene glycol

where $(\text{C}_3\text{H}_6\text{O})_y$ equals at least 10, and $(\text{C}_2\text{H}_4\text{O})_{x+x'}$ equals 10-90% of the total weight of the compound, the molecular weight being within the range of approximately 800 to approximately 10,000, and

is the radical of the halogenated monocarboxy acid

having not over 18 carbon atoms in which R' is composed of carbon and hydrogen atoms, and the halogen atom is substituted in the alpha carbon position, and $N \equiv R_1$ is the radical of the free tertiary amine $N \equiv R_1$ in which R_1 is composed of carbon and hydrogen atoms and represents not over 3 organic radicals having a total of not over 15 carbon atoms which organic radicals collectively satisfy the trivalent nitrogen valency.

5. A quaternary ammonium compound of the structure

in which ORO is the residue of the oxyethylated polypropylene glycol

where $(\text{C}_3\text{H}_6\text{O})_y$ equals at least 10, and $(\text{C}_2\text{H}_4\text{O})_{x+x'}$ equals 10-90% of the total weight of the compound, the molecular weight being within the range of approximately 800 to approximately 10,000 and

is the radical of the halogenated monocarboxy acid

having not over 2 carbon atoms in which R' is composed of carbon and hydrogen atoms, and the halogen atom is substituted in the alpha carbon position, and $N \equiv R_1$ is the radical of the free tertiary amine $N \equiv R_1$ in which R_1 is composed of carbon and hydrogen atoms and represents not over 3 organic radicals having a total of not over 15 carbon atoms which organic radicals collectively satisfy the trivalent nitrogen valency.

6. The quaternary compound of claim 5 in which $N \equiv R_1$ is a lower molecular weight alkyl derivative of pyridine having not over 9 carbon atoms.

7. The quaternary compound of claim 5 in which $N \equiv R_1$ is pyridine.

8. A quaternary ammonium compound of the structure

in which ORO is the residue of the oxyethylated polypropylene glycol

where $(\text{C}_3\text{H}_6\text{O})_y$ equals at least 10, and $(\text{C}_2\text{H}_4\text{O})_{x+x'}$ equals 10-90% of the total weight of the compound, the molecular weight being within the range of approximately 800 to approximately 10,000.

5. A quaternary ammonium compound of the structure

10 in which ORO is the residue of the oxyethylated polypropylene glycol

15 where $(\text{C}_3\text{H}_6\text{O})_y$ equals approximately 40%, and $(\text{C}_2\text{H}_4\text{O})_{x+x'}$ equals approximately 60% of the total weight of the compound, the molecular weight being within the range of approximately 800 to approximately 10,000.

20 10. A quaternary ammonium compound of the structure

25 in which ORO is the residue of the oxyethylated polypropylene glycol

30 where $(\text{C}_3\text{H}_6\text{O})_y$ equals approximately 45%, and $(\text{C}_2\text{H}_4\text{O})_{x+x'}$ equals approximately 55% of the total weight of the compound, the molecular weight being within the range of approximately 800 to approximately 10,000.

35 11. A quaternary ammonium compound of the structure

40 in which ORO is the residue of the oxyethylated polypropylene glycol

45 where $(\text{C}_3\text{H}_6\text{O})_y$ equals approximately 50%, and $(\text{C}_2\text{H}_4\text{O})_{x+x'}$ equals approximately 50% of the total weight of the compound, the molecular weight being within the range of approximately 800 to approximately 10,000.

50 12. A quaternary ammonium compound of the structure

55 60 in which ORO is the residue of the oxyethylated polypropylene glycol

65 where $(\text{C}_3\text{H}_6\text{O})_y$ equals approximately 55%, and $(\text{C}_2\text{H}_4\text{O})_{x+x'}$ equals approximately 45% of the total weight of the compound, the molecular weight being within the range of approximately 800 to approximately 10,000.

70 66 13. A quaternary ammonium compound of the structure

in which ORO is the residue of the oxyethylated polypropylene glycol

where $(\text{C}_3\text{H}_6\text{O})_y$ equals approximately 60%, and $(\text{C}_2\text{H}_4\text{O})_{x+z}$ equals approximately 40% of the total weight of the compound, the molecular weight being within the range of approximately 800 to approximately 10,000.
